UNITED STATES PATENT OFFICE

171,944

CARRYING CASE

Jerome S. Kivett, Kansas City, Mo., assignor to Regal Plastic Company, Kansas City, Mo., a corporation of Missouri

Application December 7, 1953, Serial No. 27,959

Term of patent 3½ years

(Cl. D87—5)

To all whom it may concern:

Be it known that I, Jerome S. Kivett, a citizen of the United States, residing at Kansas City, in the county of Jackson and State of Missouri, have invented a new, original, and ornamental Design for a Carrying Case, of which the following is a specification, reference being given to the accompanying drawing forming a part thereof.

Fig. 1 is a front perspective view of the carrying case, showing my new design; and

Fig. 2 is a rear perspective view of the carrying case.

I claim:
The ornamental design for a carrying case, as shown.
